ADJUSTABLE RECLINING CHAIR WITH COORDINATED LEG-REST CONTROL MEANS

Peter Stewart Fletcher, Boynton Beach, Fla., assignor to

Anton Lorenz, Boynton Beach, Fla.

Filed Nov. 5, 1958, Ser. No. 771,991

6 Claims. (Cl. 297—89)

This invention relates to articles of furniture and in particular to a new and improved reclining chair of the type in which body-supporting means are rockably mounted on a support and a leg-rest is mounted for coordinated movement with the body-supporting means.

This application contains subject matter which is common with that of my co-pending United States patent applications, Serial Nos. 495,684 and 495,685 both filed March 21, 1955 and both now abandoned, and constitutes a continuation-in-part of said application.

It is an object of the present invention to provide a reclining chair of the above-described type with a mechanism for propelling a leg-rest forwardly and upwardly during movement of the body-supporting means from a sitting position into a reclined position, the leg-rest mechanism being so arranged and constructed that the leg-rest is positioned a relatively long distance from the front edge of the seat when the seat is in an extreme reclined position, so that tall persons having long legs may rest comfortably on such a reclining chair.

Another object of the invention is the provision, in a reclining chair of the type described, of an improved leg-rest linkage construction for actuating and guiding the leg-rest in its coordinated movement with the body-supporting means, the linkage having a single connection to the seat whereby its movement is independent of movement of the seat and can be controlled to provide desired paths of movement relative to the body-supporting means without changing the general structure of the linkage.

A further object of the invention is the provision of a leg-rest actuating and guiding linkage of the character described which is so arranged and constructed as to provide a leg-rest movement in which substantially all of the outward translation of the leg-rest relative to the seat is accomplished during the initial movement of the body-supporting means at a time when the occupant's legs are disposed vertically, and during the further movement of the body-supporting means the leg-rest is rotated substantially vertically relative to the seat, thereby preventing the usual rubbing motion of the leg-rest against the legs, which rubbing motion is uncomfortable and undesirable when the full weight of the occupant's legs is on the leg-rest.

In accordance with the present invention, there is provided a reclining chair in which the body-supporting means in the nature of a back-rest and seat is movably mounted on a support frame and a leg-rest is provided with a leg-rest linkage responsive to movement of the body-supporting means. The leg-rest linkage includes a control link, a pair of rearwardly-extending links pivotally connected at spaced points to the leg-rest and a pair of depending links pivotally connected at spaced points to the control link. Pivot means are provided connecting the pair of rearwardly-extending links with the pair of depending links, with one depending link connected to both rearwardly-extending links and the other depending link connected to one of the rearwardly-extending links. The single connection of the leg-rest linkage to the seat is provided by an upstanding extension on one of the depending links which is pivotally connected to the forward portion of the seat, the other depending link terminating at the control link. The leg-rest linkage is actuated by drive means which is responsive to movement of

2

the body-supporting means and is connected to the control link for coordinated movement of the leg-rest linkage with the body-supporting means. To provide an initial forward movement and a subsequent upward movement 5 of the leg-rest, the depending link which has the extension connected to the seat, is inclined rearwardly and downwardly.

The above brief description as well as additional objects and advantages of the invention will become apparent during the course of the following specification when taken in connection with the accompanying drawings, in which:

FIG. 1 is a side elevational view of an adjustable reclining armchair according to the invention, a portion of a side wall being broken away;

FIG. 2 is a side elevational view of a different embodiment of an armchair according to the invention, a portion of a side wall being broken away;

FIG. 3 is a side elevational view of another embodiment of an armchair according to the invention, a portion of a side wall being broken away;

FIG. 4 is a side elevational view of a further embodiment of an armchair according to the invention, a portion of a side wall being broken away;

FIG. 5 is a side elevational view of still another embodiment of an armchair according to the invention, a portion of a side wall being broken away;

FIG. 6 is a side elevational view of a further embodiment of an adjustable reclining armchair according to the invention, a portion of a side wall being broken away;

FIG. 7 is a side elevational view of a different embodiment of an armchair according to the invention, a portion of a side wall being broken away;

FIG. 8 is a side elevational view of another embodiment of an armchair according to the invention, a portion of a side wall being broken away;

FIG. 9 is a side elevational view of a further embodiment of an armchair according to the invention, a portion of a side wall being broken away;

FIG. 10 is a side elevational view of still another embodiment of an armchair according to the invention, a portion of a side wall being broken away; and

FIG. 11 is a side elevational view similar to that shown in FIG. 10, wherein however the movable members of the chair are in a different position.

Referring now to FIG. 1, 10 generally indicates a support comprising side walls 12 and 14 connected with each other in any suitable manner.

A back-rest 16 and a seat 18, constituting the body-supporting means of the chair, are swingably mounted on said support 10 at 20. If desired, however, the pivotal connections between the support 10 and the back-rest 16 on one hand and the seat 18 on the other hand could be spaced from each other.

On each side of the chair the upper end of a guiding link 22 is swingably mounted on the support 10 at 24. Furthermore, on each side of the chair a downward extension 26 is rigidly connected with the back-rest 16. The rear end of a control link 28 is pivoted at 30 to the lower end of the downward extension 26 of the back-rest 16. Furthermore, said control link 28 is pivoted at an intermediate point 32 thereof to the lower end of the guiding link 22.

At its forward end, the control link 28 carries a leg-rest linkage which supports a leg-rest 46. The leg-rest linkage includes a pair of links 36 and 48 which are pivotally mounted at spaced points on the front end of the control link 28 by respective pivots 34 and 54, and which depend from said control link. The leg-rest linkage also includes a pair of rearwardly-extending links 38 and 50 which are mounted at spaced points on the leg-rest 46 by respective pivots 44 and 58. Connecting means, in the nature of pivotal connections, are provided to couple

the depending pair of links 36 and 48 with the rearwardly-extending pair of links 38 and 50. In the form of reclining chair illustrated in FIG. 1, the front depending link 36 is connected to both of the rearwardly-extending links; a pivot 56 connecting it to an intermediate point on the rearwardly-extending link 50 and a pivot 40 connecting it to the rear end of the rearwardly-extending link 38. The other depending link 48 is connected to only one rearwardly-extending link, a pivot 52 connecting it to the rear end of the rearwardly-extending link 50.

The front depending link 36 has an upstanding rigid extension 36a which projects upwardly above the pivot 34 on the control link 28, and is connected to the lower forward portion of the seat 18 by a pivot 42. On the other hand, it will be observed that the rear depending link 48 terminates at its pivotal connection 54 on the control link.

When the occupant of the chair leans the weight of his body against the back-rest 16 for urging the same into the reclined position shown in dotted line at 16' in FIG. 1, the mechanism described above causes a movement of the seat 18 from the sitting position, shown in full line, to the reclining position shown in broken line at 18'. At the same time, the leg-rest 46 is propelled forwardly and upwardly from a retracted position beneath the forward end of the seat to an extended position, shown in broken line at 46', in which it is substantially at the level of the forward end of the seat and its rear end 60' is spaced forwardly of the front end 62' of the seat. The leg-rest is spaced forwardly a considerable distance from the front end of the seat so that a tall person having long legs may comfortably rest on the chair in the reclined position.

It will be observed that a pair of connected four-bar linkages is formed by the two pairs of links, one four-bar linkage being formed by the depending link 48, the portion of the control link 28 between pivots 34 and 54, the portion of the depending link 36 between pivots 34 and 56, and the portion of the rearwardly-extending link 50 between pivots 52 and 56. The other four-bar linkage is formed by the portion of the depending link 36 between the pivots 40 and 56, the portion of the rearwardly-extending link 50 between the pivots 56 and 58, the rearwardly-extending link 38, and the portion of the leg-rest between the pivots 44 and 58. While pairs of interconnected four bar linkages have hitherto been utilized, as such, in leg-rest linkages for reclining chairs, an important feature of this invention resides in the mounting of the linkage on the control link 28 with only a single connection of the linkage to the seat 18. The leg-rest linkage is thus controlled by and guided by the control link 28, and its path of movement is not limited by the seat. Hence, upon rearward tilting movement of the back-rest, the leg-rest may be made to move in a variety of selected paths determined by regulating the path of movement of the control link 28.

As an example, it will be observed that the front depending link 36 is inclined rearwardly and downwardly from its pivotal connection 42 with the seat. Thus, when the leg-rest linkage is actuated the link 36 will pivot first forwardly and downwardly, then upwardly about its pivotal connection 42, causing the control link 28 to move forwardly and then upwardly relative to the seat. As a result, the leg-rest is guided in a first path of movement which is essentially forward, and a subsequent path of movement which is essentially upward. This has the effect of confining the outward or forward movement of the leg-rest to the initial reclining movement of the chair at a time when the user's legs are hanging downwardly. When the user's legs are raised to such a position that their weight is supported by the leg-rest, the leg-rest is travelling upwardly in the second phase of movement. Consequently, the rubbing action of the leg-rest against the legs, usually encountered in a reclining chair of this type, is wholly or substantially eliminated.

The reclining chair shown in FIG. 2 is generally similar in construction to the chair of FIG. 1 and like parts are designated by similar reference numerals, although for clarity, the numerals are preceded by the numeral "1," that is to say, they are part of a "100" series. In this view, the rockable arrangement of the back-rest 116 and the seat 118 on the support 110 and the arrangement of the linkage 122, 126 for actuating and guiding the control link 128 is the same as that described above in connection with FIG. 1.

Again the chair illustrated in FIG. 2 has a pair of depending links 148 and 136 connected at spaced points to the forward end of the control link 128 by spaced pivots 134 and 154. The leg-rest 146 is carried by the 15 pair of rearwardly extending links 138 and 150, the latter being connected to spaced points on said leg-rest by respective pivots 144 and 158. The interconnection of the pairs of links to form the connected four bar linkages differs somewhat from that shown in FIG. 1. The front 20 depending link 136 is pivoted at 170 to the rear end of the rearwardly-extending link 138 and is also pivoted at 166 to an intermediate point on the rearwardly-extending link 150. The rear depending link 148 is pivoted at 168 to the rear end of the link 150.

The front depending link 136 again has an upstanding rigid extension 136a which is pivotally connected at pivot 142 to the seat 118. The link 136 is rearwardly and downwardly inclined in the manner previously described.

The sitting position of the chair and the corresponding 30 retracted position of the leg-rest is shown in full line in FIG. 2, while the reclining position of the chair and extended position of the leg-rest is shown in broken line. The coordinated movement of the leg-rest is the same as that described previously in connection with FIG. 1.

According to the embodiment shown in FIG. 3, again the rockable arrangement of the back-rest 216 and the seat 218 on the support 210 and the arrangement of the linkage 222, 226, for actuating and guiding the control link 228 are the same as those described above in connection with FIGS. 1 and 2. Furthermore, the leg-rest linkage comprises a depending pair of links 236, 248 and a rearwardly-extending pair of links 238, 250. The front depending link 236 has an upstanding extension 236a pivoted to the seat 218 at pivot 242 and is mounted on the control link 228 at 234. The rear depending link 248 is pivotally mounted on the control link 228 by pivot 254. The front ends of the rearwardly-extending links 238, 250 are connected to the leg-rest 246 by respective pivots 244 and 258. The rear depending link 248 in this instance is connected to both rearwardly-extending links 238 and 250 by respective pivots 270, 274, while the front depending link 236 is connected to the middle of link 238 by pivot 272. The front depending link 236 is again inclined rearwardly and downwardly from its seat pivot 242.

The sitting position of the movable members of the chair is shown in full line in FIG. 3, while the extreme reclined position of the movable members of the chair is shown in broken line.

The embodiment of a chair shown in FIG. 4 again incorporates the same rockable arrangement of the back-rest 316 and seat 318 on the support 310 as the embodiments shown in the previously described FIGS. 1-3. Furthermore, again the arrangement of the guiding and actuating linkage 322, 326 for control link 328 is the same as that described in said FIGS. 1-3. The front depending link 336 is pivotally mounted on the front end of the control link 328 by pivot 334 and has an upstanding extension 336a which is pivoted to the seat 318 at 342. The rear depending link 348 is pivotally mounted at its top end on the control link 328 by pivot 354 at a point spaced rearwardly of the pivot 334. The rearwardly extending pair of links 338 and 350 are pivoted to the leg-rest 346 at 344 and 358 respectively. The rear depending link 348 is connected to both rearwardly-extending

links 338 and 350 by respective pivots 374 and 370, while the front depending link 336 is in this instance connected to the lower rearwardly-extending link 338 by a pivot 375. The front depending link is inclined rearwardly and downwardly to provide an initial forward and subsequent upward movement of the leg-rest as previously described.

The sitting position of the movable members of the chair are shown in full line in FIG. 4, while the extreme reclined position of the movable members of the chair is shown in broken line.

According to the embodiment shown in FIG. 5, the back-rest 416 and the seat 418 are rigidly connected with each other so as to form an integral unit generally indicated by 476. Said unit 476 includes a rigid downward extension 478 which is swingably mounted on the support 410 at 480, so that said unit 476 may perform rocking movements.

A first guiding link 422 is swingably mounted on the support 410 at 424. A second guiding link 482 is swingably mounted on the support 410 at 484. A control link 428 is pivoted to the lower ends of said two guiding links 422 and 482 at 432 and 486 respectively.

The leg-rest control substantially corresponds to the mechanism shown in FIG. 1. Again the pair of depending links 436 and 448 are pivotally mounted at spaced points on the forward end of the control link 428 by pivots 434 and 454. The front depending link 436 has an upstanding extension 436a connected to the seat at 442. The front ends of the rearwardly-extending pair of links 438 and 450 are pivoted to spaced points on the leg-rest 446 by respective pivots 444 and 458. The front depending link 436 is connected to both rearwardly extending links 438 and 450 by respective pivots 440 and 456, while the rear depending link is connected to link 450 by pivot 452. The front depending link 436 again extends rearwardly and downwardly from its seat pivot 442.

When a person resting on the chair rocks the unit 476 around the pivot 480 from the sitting position shown in full lines into the reclined position 476' shown in broken line, the leg-rest 446 is moved upwardly and forwardly by means of the above-described linkage from the retracted position shown in full line to the extended position shown in broken line at 446'. In said extended position 446', the upper edge of the leg-rest is at a larger distance from the front edge of the seat than in the retracted position. In this instance the drive for the leg-rest movement is produced by the upward movement of the seat at pivot 442, but the leg-rest movement is still substantially independent of the seat and is guided and controlled entirely by control link 328 to produce the movements previously described. The control link movement is in turn controlled by the guiding links 422 and 482, and its movement cooperates with the downwardly and rearwardly-inclined link 436 to produce an initial forward and subsequent upward movement of the leg-rest.

In the various embodiments of reclining chairs heretofore illustrated in FIGS. 1 to 5, the front depending link has been provided with an upstanding extension connected to the seat and constituting the only connection of the leg-rest linkage to the seat. In accordance with my invention, alternate structures may be produced in which the rear depending link has the upstanding extension connected to the seat. FIGS. 6 to 11 illustrate such forms of the invention.

In the embodiment shown in FIG. 6, the back-rest 516 and seat 518 are made as independently-movable elements and both are mounted on the support 510 at a common pivot 520. The control link 528 is supported and guided by the guiding link 522 which is connected by pivot 532 to an intermediate point on the control link. The rear end of the control link 528 is connected by pivot 530 to a depending extension 526 of the back-rest 516 for actuation in response to tilting movement of said back-rest.

A pair of depending links 534 and 538 are mounted at

the forward end of the control link 528 by respective pivots 546 and 550. A pair of rearwardly-extending links 536 and 540 are connected at spaced points on the leg-rest 552 by respective pivots 554 and 556. The rear depending link 538 is connected to the ends of both rearwardly-extending links 536 and 540 by respective pivots 562 and 544. The front depending link 534 is connected to an intermediate point on the link 536 by a pivot 542.

In this instance, the rear depending link 538 has the 10 upright rigid extension 538a extending above the pivot 550 and connected to the forward end of the seat 518 by pivot 548. Again, the leg-rest linkage is mounted for movement independently of the seat, because of this single seat connection, the path of movement of the leg-rest being determined by the movement of the control link 528. Again, the link connected to the seat, in this instance the rear depending link 538, is inclined rearwardly and downwardly to provide an initial forward movement of the leg-rest and a subsequent upward movement, as previously described.

According to the embodiment shown in FIG. 7, again the rockable arrangement of the back-rest 616 and the seat 618 on the support 610 and the arrangement of the guiding linkage 622, 626, 628 are the same as those of the embodiment shown in FIG. 6.

Again the chair illustrated in FIG. 7 has a pair of depending links 634 and 638 connected at spaced points to the forward end of the control link 628 by spaced pivots 646 and 650. The leg-rest 652 is carried by the pair of rearwardly-extending links 636 and 640, the latter being connected to spaced points on said leg-rest by respective pivots 654 and 656. The interconnection of the pairs of links to form the connected four bar linkages differs somewhat from that shown in FIG. 6. The front depending link 634 is pivoted at 642 to the rear end of the rearwardly-extending link 636, and is also pivoted at 666 to an intermediate point on the rearwardly-extending link 640. The rear depending link 638 is pivoted at 644 to the rear end of the link 640.

40 The rear depending link 638 again has an upstanding rigid extension 638a which is pivotally connected at pivot 648 to the seat 618. The link 638 is rearwardly and downwardly inclined in the manner previously described.

The sitting position of the chair and the corresponding 45 retracted position of the leg-rest is shown in full line in FIG. 7, while the reclining position of the chair and extended position of the leg-rest is shown in broken line. The coordinated movement of the leg-rest is the same as that described previously in connection with FIG. 6.

According to the embodiment shown in FIG. 8, again the rockable arrangement of the back-rest 716 and the seat 718 on the support 710 and the arrangement of the linkage 772, 726 for actuating and guiding the control link 728 are the same as those described above in connection with FIGS. 6 and 7. Furthermore, the leg-rest linkage comprises a depending pair of links 734, 738 and a rearwardly-extending pair of links 736, 740. The rear depending link 738 has an upstanding extension 738a pivoted to the seat 718 at pivot 748 and is mounted on the control link 728 at 750. The front depending link 734 is pivotally mounted on the control link 728 by pivot 746. The front ends of the rearwardly-extending links 736, 740 are connected to the leg-rest 752 by respective pivots 754 and 756. The front depending link 734 in this instance is connected to both rearwardly-extending links 736 and 740 by respective pivots 766, 768, while the rear depending link 738 is connected to the end of link 740 by pivot 770. The rear depending link 738 is again inclined rearwardly and downwardly from its seat pivot 748.

The sitting position of the movable members of the chair is shown in full line in FIG. 8, while the extreme reclined position of the movable members of the chair is shown in broken line.

The embodiment of a chair shown in FIG. 9 again incorporates the same rockable arrangement of the back-

rest 816 and seat 818 on the support 810 as the embodiment shown in the previously described FIGS. 6-8. Furthermore, again the arrangement of the guiding and actuating linkage 822, 826 for control link 828 is the same as that described in said FIGS. 6-8. The rear depending link 838 is pivotally mounted on the forward end of the control link 828 by pivot 850 and has an upstanding extension 838a which is pivoted to the seat 818 at 848. The front depending link 834 is pivotally mounted at its top end on the control link 828 by pivot 846 at a point spaced forwardly of the pivot 850. The rearwardly-extending pair of links 836 and 840 are pivoted to the leg-rest 852 at 854 and 856 respectively. The rear depending link 838 is connected to both rearwardly-extending links 836 and 840 by respective pivots 872 and 871, 15 while the front depending link 834 is in this instance connected to the lower rearwardly-extending link 836 by a pivot 873. The rear depending link 838 is inclined rearwardly and downwardly to provide an initial forward and subsequent upward movement of the leg-rest as previously described.

The sitting position of the movable members of the chair are shown in full line in FIG. 9, while the extreme reclined position of the movable members of the chair is shown in broken line.

According to the embodiment shown in FIGS. 10 and 11, the back-rest 916 and the seat 918 are rigidly connected with each other so as to form an integral unit generally indicated by 974. Said unit 974 includes a rigid downward extension 976 which is swingably mounted on the support 910 at 978, so that said unit 974 may perform rocking movements.

A first guiding link 922 is swingably mounted on the support 910 at 924. A second guiding link 980 is swingably mounted on the support 910 at 982. A control link 928 is pivoted to the lower ends of said two guiding links 922 and 980 at 932 and 984 respectively.

A pair of depending links 934 and 938 are pivotally mounted at spaced points on the forward end of the control link 928 by pivots 946 and 950. The rear depending link 938 has an upstanding extension 938a connected to the seat at 948. The front ends of the rearwardly-extending pair of links 936 and 940 are pivoted to spaced points on the leg-rest 952 by respective pivots 954 and 956. The front depending link 934 is connected to both rearwardly-extending links 936 and 940 by respective pivots 942 and 968, while the rear depending link 938 is connected to link 940 by pivot 944. The rear depending link 938 again extends rearwardly and downwardly from its seat pivot 948.

When a person resting on the chair rocks the unit 974 around the pivot 978 from the sitting position shown in FIG. 10 into the reclined position shown in FIG. 11, the leg-rest 952 is moved upwardly and forwardly by means of the above-described linkage from the retracted position shown in FIG. 10 to the extended position shown in FIG. 11. In said extended position of FIG. 11, the upper edge of the leg-rest is at a larger distance from the front edge of the seat than in the retracted position. In this instance the drive for the leg-rest movement is produced by the upward movement of the seat at pivot 948, but the leg-rest movement is still substantially independent of the seat and is guided and controlled entirely by control link 928 to produce the movements previously described. The control link movement is in turn controlled by the guiding links 922 and 980, and its movement cooperates with the downwardly and rearwardly-inclined link 938 to produce an initial forward and subsequent upward movement of the leg-rest.

It should be observed that in the various embodiments of the invention illustrated herein, either one or the other of the two depending links are connected to the seat, but in either instance the single connection to the seat provides a movement of the leg-rest which is not controlled by the seat. In addition, in each instance the

depending link which is connected to the seat is inclined downwardly and rearwardly from such point of connection.

While preferred embodiments of the invention have been shown and described herein, it is obvious that numerous additions, changes, and omissions may be made without departing from the spirit and scope of the invention.

For example, each of the embodiments may be provided with means for limiting the sitting and extreme reclined positions and furthermore with means for locking the movable members of the chair in any desired position.

What is claimed is:

1. A reclining chair including a support, body-supporting means including a seat and a back-rest, means movably mounting said body-supporting means on said support for tilting movement, a leg-rest, a leg-rest linkage, said leg-rest linkage including a control link, a first pair of links pivoted together with the free end of one link pivoted to the control link at its forward end at a first control pivot, a second pair of links pivoted together with the free end of one link pivoted to the control link at a second control pivot spaced from said first control pivot, the free ends of the other links of said pairs being operatively connected to said leg-rest, and coordinated means coupling said pairs of links to constrain said leg-rest to move in a predetermined path relative to said control link, mounting means mounting said control link on said support for turning movement relative to said seat, said mounting means including a guide link pivotally mounted on the support and pivoted to an intermediate point on said control link, said turning movement of said control link being determined substantially by the action of said guide link to guide said control pivots in predetermined paths relative to said support, actuating means operatively connecting one of said pairs of links and said control link to said body-supporting means including a rigid extension of one of said one links of said pairs of links beyond its pivotal connection to said control link, said extension being operatively connected to said seat, said actuating means also including means operatively connecting the body-supporting means to the rear portion of said control link for coordinating movement of said leg-rest with the movement of said body supporting means, said pairs of links being actuated at one rate and said control link at another rate by said actuating means in dependence on said tilting movement of said body-supporting means to guide said leg-rest relative to said support in a path determined by said path of said leg-rest relative to said control link, said paths of said control pivots, and said rates of actuation of said pairs of links and said control link.

2. A reclining chair including a support, body-supporting means including a seat and a back-rest, means movably mounting said body-supporting means on said support for tilting movement, a leg-rest, a leg-rest linkage, said leg-rest linkage including a control link, a first pair of links pivoted together with the free end of one link pivoted to the control link at its forward end at a first control pivot, a second pair of links pivoted together with the free end of one link pivoted to the control link at a second control pivot spaced rearwardly from said first control pivot, the free ends of the other links of said pairs being operatively connected to said leg-rest, and coordinated means coupling said pairs of links to constrain said leg-rest to move in a predetermined path relative to said control link, mounting means mounting said control link on said support for turning movement relative to said seat, said mounting means including a guide link pivotally mounted on the support and pivoted to an intermediate point on said control link, said turning movement of said control link being determined substantially by the action of said guide link to guide said control pivots in predetermined paths relative to said support,

actuating means operatively connecting one of said pairs of links and said control link to said body-supporting means including a rigid extension of one of said one links of said pairs of links beyond its pivotal connection to said control link, said extension being operatively connected to said seat, said actuating means also including a portion of said body-supporting means connected to the rear portion of said control link for coordinating movement of said leg-rest with movement of said body-supporting means, said pairs of links being actuated at one rate and said control link at another rate by said actuating means in dependence on said tilting movement of said body-supporting means to guide said leg-rest relative to said support in a path determined by said path of said leg-rest relative to said control link, said paths of said control pivots, and said rates of actuation of said pairs of links and said control link.

3. A reclining chair according to claim 2 in which said actuating means includes a depending extension of said back-rest connected to the rear portion of the control link.

4. A reclining chair according to claim 2 in which said one link of the first pair has said rigid extension.

5. A reclining chair according to claim 2 in which said one link of the second pair has said rigid extension.

6. A control arrangement for use in a reclinable chair construction including: a support, a trio of body supporting components consisting of a seat mounted on said support and a back rockable on said support between sitting and reclining positions and a leg rest supported relative to said seat for movement between an inoperative generally vertically disposed position and an operative generally horizontally disposed forwardly extended position, a pair of coacting linkage systems, each linkage sys-

tem of said pair thereof consisting of; an extension comprising the lower portion of said back extending downwardly from its connection at said support, a primary link pivotally connected to a forward portion of said seat, a secondary link spaced from said seat and back and support, said extension and primary and secondary links being spaced from each other, an actuating link interconnecting and in pivotal engagement with said extension and primary and secondary links, a pair of spaced leg rest links including a primary leg rest link and a secondary leg rest link each having forward end portions pivotally connected to said leg rest, one of said primary and secondary links being pivotally connected to one of the leg rest links of said pair thereof and the other of said primary and secondary links pivotally interconnecting the two leg rest links of said pair thereof and the leg rest links of said pair thereof constituting a shiftable linkage system with the interconnection of said secondary and actuating links being shiftable forwardly relative to the interconnection of said primary link and said seat upon the forward movement of said extension and with the distance between the pivotal connection connecting said seat and primary link and the pivotal connection connecting said secondary and actuating links increasing as said back is moved from the sitting position to the reclined position.
